UNITED STATES PATENT OFFICE.

FRANK L. NICHOLS, OF STAMFORD, CONNECTICUT, ASSIGNOR TO INTERNATIONAL MUNITIONS COMPANY INC, OF DELAWARE.

MUNITIONS ORGANIZATION.

1,324,613.

Specification of Letters Patent.

Patented Dec. 9, 1919.

Application filed June 14, 1919. Serial No. 304,130.

To all whom it may concern:

Be it known that I, FRANK L. NICHOLS, a citizen of the United States of America, residing at Stamford, in the county of Fairfield and State of Connecticut, have invented certain new and useful Improvements in Munitions Organizations, of which the following is a specification.

The invention relates to a novel bomb or grenade thrower embodying the employment of the ordinary service rifle cartridge as a propelling agent to discharge or throw the bomb.

Referring to the accompanying drawings which form a part of this specification:

Figure 1 represents a top view partly in section of the bomb thrower.

Fig. 2 is a side elevation partly in section.

Fig. 3 is a detail view to a larger scale.

Fig. 4 shows the appearance of the cartridge after it has been fired.

In these drawings 10 represents the central portion of an Army rifle, with trigger 11, channel 12 for firing pin, and cartridge shell with-drawing pin 12*. This portion of the mechanism need not be particularly described as it is well known in the art; suffice it to say that from the point 13 to the point 14, with all the parts inclusive, the bomb thrower is exactly the same as a regular service rifle; locks and contiguous parts of rifles that have been damaged from one cause or another can be used for this purpose if desired; this constitutes a salvage and is of value from an economic standpoint; the rifle barrel itself is done away with.

At the point 13 is provided a screw threaded portion which intermeshes with the thread 16 of the stock 17, which latter may be of any desired construction; as here engineered this form is suitable, by means of its end or base piece 18, for bracing the implement against the ground, or a trench wall, or any other convenient support when the implement is to be employed.

As before stated the ordinary rifle barrel is eliminated, the lock case proper terminating at the point 14; screwed on to this at 19 is a casing 20 enlarged at its outer end 21 and having attached to it, as by a screw joint 22, the major bore 23 of the implement; the bomb or major missile 24 is shown in place, that is to say, in firing position in said major bore.

It will be noted that below the bomb 24

and between it and the inner end of the major bore 23 is a chamber 25 which is inwardly continued by the smaller chamber 26; the chambers 25 and 26 combine and constitute the explosive, and expanding, 60 chamber for the gases of the functioned cartridge 27.

This cartridge is shown as stated at 27 and is the ordinary service cartridge of the Army rifle; the bullet or minor missile is shown 65 at 28 and after the cartridge has functioned in the chamber 29, the said bullet passes into the chambers 26, 25, and from thence through the major missile, or bomb, 24 as will be explained. The casing 29 is fitted 70 into the casing 20 and forms, when the parts are assembled, a close-fitting and interlocked member; the casing 29 constitutes the explosive unit chamber or minor missile bore and it is in line with, and to the rear, of the 75 major missile bore 23.

The manner of utilizing the explosive nature of the cartridge is through a by-pass system engineered as follows: At the point 30 is a port extending through the casing 80 29 and entering a channel 31. This is effected by boring through the walls of the casing 20 and then through the inner wall of the channel 31 and wall of the casing 29; 32 affords temporary means of entrance for 85 the boring tool to properly engineer the port or opening 30; this port is disposed to the rear of the bullet 28 when the latter is positioned and the temporary entrance 32 is subsequently permanently sealed by a plug 90 as shown. When the explosive functions in the cartridge, it will shear through the side walls of the cartridge shell and the explosive gases will effect a passage through the by-pass system that is to say, through the 95 port 30, into the channel 31 and from thence to the chamber 25.

When the minor missile, or bullet, 28 is discharged it leaves the cartridge casing, passing through the chamber 26 into the 100 chamber 25 and from this point enters the bullet hole 34 of a collapsible sealer 35 and thence through the bullet tube 36. When the bullet has entered the bullet tube the explosive gases passing through the port 30 105 and chamber 31 have arrived in the chamber 25 resulting in the crushing of the collapsible sealer 35. Before the bullet leaves the bullet tube it side swipes the primer 37.

By referring to Fig. 3, the parts are shown 110

in position ready for firing. The shell or envelop 33 of the cartridge covers the port or opening 30, seals it in fact, so long as the cartridge is not functioned; when, however, the cartridge functions, the explosive force of the gases contained, or generated in the cartridge, will shear through the envelop 33 at, and in, the area registering with the port 30, and permit the explosive gases 5 to enter directly into the channel 31, and 10 to enter directly into the chamber 25; this operation will cause the expulsion of the major missile.

As will be seen from the foregoing the 15 minor missile or propelling unit coordinates with a breech loading mechanism while the major missile is loaded from the muzzle; it will also be seen that the bores and the missiles are centrally alined.

20 The lateral movement of the explosive gases, through and by means of a side thrust, or a burst sidewise of a portion of the shell body or explosive container, of the cartridge permits me to combust more quickly and I 25 am thereby enabled to deliver a sharper initial blow upon the base of the major missile; this sharp initial blow is of great value owing to the shortness of the major missile bore; it results in an increased range.

30 I claim:

1. A munition organization embodying alined major and minor missile bores, major and minor missile units, means for functioning the explosive powder of the minor missile unit by a sidewise burst of its container, means for conveying the resultant explosive gases to the base of the major missile and simultaneously discharging the minor missile.

40 2. An organization embodying alined major and minor bores, a major missile, a service cartridge, means for functioning the cartridge and thereupon thrusting a portion of the cartridge shell body aside and permitting the explosive gases to escape and 45 means for conveying said gases to the base of the major missile.

3. A munition organization embodying a muzzle loading major missile bore and a breech loading minor missile bore, said bores

being in alinement, a major missile, a service cartridge positioned in the minor missile bore, and means for effecting a lateral rupture of the cartridge shell.

4. A munition organization embodying a 55 breech loading explosive unit chamber, a muzzle loading major missile bore positioned in front of and directly in line therewith, a by-pass channel having a port in the chamber and connecting said chamber 60 to the base of said bore, an explosive unit having a container for closing the port, and means for functioning said explosive unit and opening said by-pass by shearing its container.

5. A munition organization embodying a minor missile chamber, a major missile bore positioned in front and directly in line therewith, a by-pass connecting said chamber to the base of said bore, and a service cartridge 70 so disposed in the minor missile chamber as to close the port of the by-pass and to position the bullet of the cartridge to the fore of the port, whereby when the cartridge functions the explosive gases will shear 75 through the cartridge case into the said by-pass.

6. A munition organization embodying a minor missile chamber, a minor missile having an explosive container, a major missile 80 bore positioned in front and directly in line therewith, a major missile, a channel extending rearwardly from said bore, a by-pass connecting said channel with the minor missile chamber at a point to the rear of 85 the bullet when positioned therein, whereby when the cartridge functions the explosive gases will shear through the cartridge case into the said by-pass.

7. The combination in a munition organization of a major missile bore having a major missile embodying a centrally positioned bullet tube, a cartridge chamber lying directly to the rear and concentric therewith, a cartridge, means for functioning same by 90 side thrusting a portion of the shell body of the cartridge and means for conveying the resultant gases to the base of the major missile.

FRANK L. NICHOLS.
